United States Patent Office.

M. J. ALTHOUSE, OF WAUPUN, WISCONSIN.

Letters Patent No. 63,454, dated April 2, 1867.

IMPROVEMENT IN PUMP-PISTON PACKING.

The Schedule referred to in these Letters Patent and making part of the same.

TO ALL WHOM IT MAY CONCERN:

Be it known that I, M. J. ALTHOUSE, of Waupun, in the county of Fond du Lac, and State of Wisconsin, have invented a new and useful Improvement on Packing for Pump-Buckets; and I do hereby declare that the following is a full, clear, and exact description thereof, reference being had to the accompanying drawings, making a part of this specification, in which—

Figure 1 is an external view of a wooden pump-bucket with my improved packing applied to it.

Figure 2 is a horizontal section through fig. 1, taken at the point *xx*.

Figure 3 is a vertical section through the pump-bucket.

Figure 4 is a horizontal section through the pump-bucket, taken above the valve.

Figure 5 is a sectional view, similar to that of fig. 3, showing the packing contracted.

Figure 6 shows two of the packing rings.

Similar letters of reference indicate corresponding parts in the several figures.

This invention relates to a new and improved expansible packing, which is applicable to the wooden pump-bucket shown and described in my Letters Patent dated on the 13th day of November, 1866.

The nature of my invention consists in an expansible packing, which is composed of a soft substance, such as leather or India rubber, and a hard substance, such as metal or wood, applied in the form of rings within an annular chamber formed in the circumference of a pump-bucket piston, in such manner that the pressure of the column of water above the piston will, when desired, cause an expansion of the hard and soft rings, and thus pack the piston in its upward strokes, as will be hereinafter explained. It also consists in protecting the outer edge of a soft expansible packing ring from being crowded out of place, and rapidly worn out, by means of expansible rings of wood, metal, or other inflexible substance, applied on both sides of the softer ring, as will be hereinafter described.

To enable others skilled in the art to understand my invention I will describe its construction and operation.

In the accompanying drawings, A represents the hollow cylindrical piston-head of the pump-bucket, and B is the arched stock or extension, to which the piston-rod is attached. C represents the ordinary valve used for pump-buckets, for covering the central opening through the piston-head A; and *a* represents an annular recess, which is made in the circumference of the head A for receiving the packing, as shown in figs. 2, 3, and 5. Two holes *bb* are made through the upper portion of the piston-head, which holes enter the annular chamber *a* behind the packing, and allow the column of water, which is above head A when it is raised, to press the packing outward against the bore of the pump. When the packing is new it is designed to have it fit snugly against the bore of the pump without pressing it outward by the water, as above stated; for which purpose the passages *bb* can be closed by the valves or cut-off plates *cc* on top of the piston. When the packing becomes considerably worn, so as to work loose, the valves *cc* are opened more or less, to allow the weight of water above the piston to get behind and press out the packing. Within the annular recess *a* I introduce packing rings D E, the outer edges of which project slightly beyond the circumference of the piston-head, so as to press with greater or less force against the bore of the pump-stock. The intermediate ring D may be made of leather, as shown in figs. 2 and 6, or it may be made of India rubber, as shown in figs. 2 and 5. If this ring is of leather it must be "cut" as shown in fig. 6, to allow of its application in its recess *a*; but if this intermediate ring is of India rubber it need not be "cut," as it can be stretched and passed over the piston-head and into its recess. The width of these intermediate rings should be such as to leave a space behind them, as shown in the sectional views of the drawings. The rings E may be made of wood, as in fig. 3; or of metal, as in figs. 5 and 6; or of any other hard and inflexible substance. They should be made of two or more sections, so that they will expand simultaneously with the intermediate packing ring D, and sustain that portion of this latter ring which is exposed beyond the circumference of the piston-head A, as shown in fig. 3. The metallic or wooden rings may be made in two sections; but I prefer to divide each one of these rings into three sections or segments, as shown in fig. 6, so that they will expand and contract uniformly, and afford a better support for the softer rings, which are placed between them. It will be seen from the above description that the outer edge of the soft packing ring D is confined and supported between upper and lower expansible rings, which latter will prevent the said projecting portion of the soft packing from being crushed upward or downward.

Having described my invention, what I claim as new, and desire to secure by Letters Patent, is—

1. Providing for sustaining a leather, rubber, or other soft packing, between expandible rings or segments, so as to protect the exposed portions of the soft packing, substantially as described.
2. The combination of the expandible hard metal or wood rings and the rubber or other soft rings, all constructed and applied substantially in the manner and for the purpose herein described.

M. J. ALTHOUSE.
